[57] CLAIM

The ornamental design for an aquarium filter, substantially as shown and described.

DESCRIPTION

FIG. 1 is a top plan view of an aquarium filter showing my new design;
FIG. 2 is a front elevational view thereof;
FIG. 3 is a right side elevational view thereof, the left side being a mirror image of the right side shown;
FIG. 4 is a rear elevational view thereof; and
FIG. 5 is a bottom view thereof.

FIG.1

FIG.2

FIG.3

FIG. 4

FIG. 5
